WILLIAM A. HANCOCK, OF SEYMOUR, CONNECTICUT, ASSIGNOR TO THE SEYMOUR METAL GOODS COMPANY, OF SEYMOUR, CONNECTICUT, A CORPORATION OF CONNECTICUT.

SAFETY ATTACHMENT FOR PRESSES.

1,128,779.

Specification of Letters Patent. Patented Feb. 16, 1915.

Application filed November 17, 1914. Serial No. 872,638.

To all whom it may concern:

Be it known that I, WILLIAM A. HANCOCK, a citizen of the United States, residing at Seymour, county of New Haven, State of Connecticut, have invented an Improvement in Safety Attachments for Presses, of which the following is a specification.

This invention has for its object to provide, a simple, inexpensive and easily attached safety device adapted for use upon foot and power presses, which will effectually protect the operator from injury by getting a hand or finger caught between the punch and the die or die block.

With this end in view I have devised the novel attachment which I will now describe, referring to the accompanying drawings forming a part of this specification and using reference characters to indicate the several parts.

Figure 1 is a side elevation of a press showing the application thereto of my novel attachment, the punch being raised and the guard in the retracted position; Fig. 2 a similar view showing the punch lowered and illustrating the operation of the guard in use, and Fig. 3 is a front elevation of the press, the view corresponding with Fig. 1 as seen from the left.

As the attachment is equally applicable to all sizes and styles of punching, stamping and drawing presses, I have not illustrated and will not describe a press in detail, and will refer only to the parts co-operating with the attachment.

10 denotes the punch holder, 11 the punch and 12 the die block, all of which may be of any ordinary or preferred construction, depending of course upon the work to be performed.

The essential feature of the invention is a guard 13, operated by descent of the punch holder, which lies back of the line of movement of the punch when the latter is in the raised position, moves forward as the punch descends, just clearing the punch, and acts effectively to push the hand or hands of the operator away from the punch before it reaches the lowered position, thus making injury to the operator by the punch practically impossible, the punch being behind the guard during the latter portion of its downward movement. The guard is formed integral with or is secured to a lever 14, shown as

slightly curved, which is pivoted as at 15, to an arm 16 rigidly secured to the punch holder. I have shown the long arm of the lever as off-set as at 17, so as to carry the lower end thereof appreciably to one side 60 of the punch and the guard as extending substantially at a right angle from the lever. It will be noted that the plane of the guard is substantially parallel with the front of the die block, and that the guard extends an 65 appreciable distance on each side of the punch. This is in order to give sufficient sweep to the guard to insure the removal of the operator's hands from under the punch under all conditions of use. The special shape or configuration of the guard is wholly immaterial so far as the invention is concerned. The essential feature is that the guard be given sufficient sweep and that as the punch descends it move from the 70 position shown in Fig. 1 toward the position shown in Fig. 2. In the present instance I have shown the guard as provided with an offset shoe 18 which slides over the die block, thereby reducing the contact surface of the guard with the die block, and providing clearance for work that may project above the surface of the die block. The short arm of the lever extends beyond the pivot, and a spring 19, the ends of which are shown as connected respectively to arm 16 and to the short arm of the lever, acts to retain the guard in engagement with the upper surface of the die block. This spring is preferably used but is not essential.

Having thus described my invention I claim:

1. The combination with the punch carrier and die block of a press, of a guard normally lying back of the line of movement of the punch and resting on the die block, a lever by which said guard is carried and an arm extending from the punch carrier to which the lever is pivoted, downward movement of the punch carrier causing forward movement of the guard, the guard clearing the punch and the downward movement of the latter continuing behind the guard.

2. The combination with the punch carrier and die block of a press, of a guard normally lying back of the line of movement of the punch and resting on the die block and a pivoted lever by which said guard is carried.

3. The combination with the punch carrier and die block of a press, of a guard normally lying back of the line of movement of the punch and resting on the die block, a pivoted lever by which said guard is carried, and a spring acting to retain the guard in operative position.
4. The combination with the punch carrier and die block of a press, of a guard normally lying back of the line of movement of the punch and resting on the die block, a lever whose long arm carries the guard, an arm extending from the punch carrier to which the lever is pivoted and a spring con-
- ected to the short arm of the lever and to 15 said arm.
5. The combination with the punch carrier and die block of a press, of a guard normally lying back of the line of movement of the punch and having a shoe which slides 20 over the die block, and a lever by which the guard is carried.

In testimony whereof I affix my signature in presence of two witnesses.

WILLIAM A. HANCOCK.
